UNITED STATES PATENT OFFICE.

CHARLES A. FINLEY, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE EQUIPMENT.

1,242,672.

Specification of Letters Patent.

Patented Oct. 9, 1917.

Application filed May 20, 1916. Serial No. 98,781.

To all whom it may concern:

Be it known that I, CHARLES A. FINLEY, a citizen of the United States, residing at Brooklyn, in the county of Kings and State of New York, have invented certain new and useful Improvements in Telephone Equipment, of which the following is a full, clear, concise, and exact description.

This invention relates to telephone equipments, and more particularly to improvements in telephone equipments for use in helmets as employed in mine-rescue service, firemen's work and in connection with diving operations.

The principal object of this invention is to provide a simple and efficient arrangement whereby a telephone transmitter unit, removably placed within a helmet, is operated by reflected sound waves, and while normally in position for instant use, is least affected by moisture and is not acted upon by the respiration of a wearer or by extraneous sounds which have been found to set up disagreeable side tones in the equipments of this character heretofore employed.

In accordance with this invention, a helmet is provided with a transmitter unit placed in an inverted position in alignment with the position normally occupied by the mouth of the wearer of the helmet. The transmitter unit is provided with prong-like feet adapted to be sprung into a cup-like vent chamber regularly present in the wall of the helmet for reducing the pressure of air therein. The vent chamber supports the transmitter unit and also serves to reflect sound waves to act on the diaphragm thereof.

This invention is illustrated in the accompanying drawing, in which Figure 1 is a perspective front view of a face mask helmet suitable for illustrating the features of this invention.

Fig. 2 is a side sectional view of the face mask, shown in Fig. 1, seated on the head of a wearer as in actual use.

Fig. 3 is a rear view of the transmitter button assembled in a suitable supporting mounting.

Fig. 4 is a combined sectional and perspective side view of the transmitter button shown in Fig. 3 placed in position within the vent cut of the helmet.

Fig. 5 is a view showing in detail the vari-

ous parts comprising the assembly of the transmitter unit.

In describing this invention in connection with the drawings, the face mask 3, provided with windows 4 and 5, is adapted to be secured to the head of a wearer by means of the straps 6, after which an inner pneumatic cushion 7 of comparatively circular form is inflated by means of a bulb pump 8 to press snugly against the face of the wearer and thereby form an air-tight chamber in which the respiratory organs open. Suitable ducts 9 extend to a point from which air is thereby supplied to the helmet. A circular vent chamber 15 is provided with an outer sealing cap 16 which carries a screw threaded stud 17. The cap may be rotatively worked in a threaded spider 18 to permit the exhaust of excess air pressure or to enable the user to obtain air directly from the surrounding atmosphere, if desired, or may be screwed down to clamp the gasket material 19 between the rim of the chamber 15 and the outer cap 16 to thereby seal the air compartment of the helmet. The transmitter button is of circular form and comprises a cup 20, the outside wall of which is reduced in diameter near its rim to form a shoulder at the bottom portion of the wall, and a male screw thread is formed on the reduced portion of the wall extending downwardly from the top of the cup, as shown in Fig. 5. A circular electrode button 25 is suitably attached to the inside bottom of the cup and the inner wall of the cup is covered with an insulating lining 26. A washer 35 of suitable resilient material is placed over the reduced portion of the cup which is then inserted through a circular opening 37 in a holder 36. Comminuted material 27 is placed within the cup and a diaphragm 29, preferably of insulating material, carrying a circular electrode button 28, is placed over the mouth of the cup with the button entering therein and engaging the comminuted material 27. A suitably flanged and threaded ring nut 30 may then be screwed on to the cup 20 to thereby clamp the periphery of the diaphragm 29 to the top of the cup wall, and, at the same time, bind the holder 36 and the resilient washer 35 against the shoulder of the cup. Suitable prong-like feet 38, formed as a tripod with the holder 36, are curved to stand in the circular vent chamber 15 and

90

105

press outwardly against the wall thereof to retain the assembled transmitter in position. An extended portion 39 of the support 36 carries a terminal screw 45 insulated therefrom by a suitable bushing 46 and washers 47. A flexible conductor 48 connects this terminal 45 to an outer metal detail 31, which makes electrical contact with the electrode 28 in clamping the latter to the dia- 5 phragm 29. A second terminal screw 50 is in electrical connection with the supporting frame 36 and, through the contact of the frame 36 with the ring nut 30, establishes a connection through the metal cup 20 to the rear electrode 25.

From the terminals 45 and 50 of the transmitter, flexible conductors 51 and 52 extend to terminals posts 55 and 56 attached to extend through but suitably insulated from 10 a metal connector 10 of the air duct 9. From these terminals, conductors may be routed exterior to an extended air duct (not shown) which may be coupled to the tube 9, or if desired, the conductors may be routed through 15 the inside of such air tube extension.

In operation, sound waves set up by the voice of a person wearing the helmet first strike the bottom or solid back of the transmitter cup 20 and therefore do not at that 20 affect the transmitter. Continuing, however, these sound waves enter the vent chamber 15 and are reflected back by the sealing disk 16 and the spider 18 to arrive 25 at and act upon the transmitter diaphragm 29. The relatively limited area of this diaphragm and its characteristics as to flexibility, combined with the indirect application of sound waves thereto, result in 30 clear and efficient telephonic transmission. Moisture, resulting from the respiration of 35 a wearer of the helmet, collects at the rear of the transmitter and does not, to an appreciable extent, reach the diaphragm or working parts thereof. And further, in 40 view of the proximity of the vent chamber to the working parts of the transmitter, condensations due to the air exhaled by a wearer are more readily carried away each 45 time the vent is opened. The present method of providing that the respirations of a wearer take place adjacent the solidly 50 fixed rear of the transmitter unit, results in preventing such breathing disturbances, as set up in the confined air of the helmet, 55 having an appreciable effect on the dia- phragm 29. Therefore, breathing operations 60 do not cause disagreeable side tones in a distant receiver (not shown) to which this transmitter may be connected. On re- 65 moving the helmet, the transmitter unit may be readily lifted from its position in the helmet without expert knowledge or the use of tools, and, in this way, is conveniently accessible for cleaning as to any moisture which may adhere thereto. The vent

chamber 15 is also rendered accessible at the same time for similar cleaning operations, after which the transmitter may be instantly reseated in its working position, all without the use of tools.

A distinct advantage of the present invention is the compact and relatively midget proportions of this transmitter unit making it light, non-cumbersome and mechanically rugged for this hazardous and exacting 70 75 service.

From the foregoing description of this equipment, it will be readily apparent that the characteristic size and position of the working parts of this transmitter with respect to the action of air waves thereon, while practically unresponsive to ordinary aural disturbances, are nevertheless sensitive to and respond efficiently when waves corresponding with those of articulate 80 85 speech are applied thereto in an indirect manner as described.

Although this invention has for convenience been illustrated and described in connection with a specific type of face helmet, 90 it will be understood that its scope is not limited thereto, and that the features of this invention may be applied to the various types of helmets or diving suits in connection with which telephone service of this 95 character may be desirable. It will also be understood that a suitable source of current, as batteries for the transmitter, may be carried by a wearer of the helmet or that such current may be supplied from a distant telephone station at which the exterior conductors may terminate.

What is claimed is:

1. In a helmet having a recess therein, a transmitter unit, and supporting means for 105 said unit having resilient feet adapted to engage the walls of said recess to removably secure said unit within said helmet.
2. In a telephone equipment, a helmet, a transmitter having movable parts arranged 110 at one side thereof, means to mount said transmitter within said helmet, the movable parts thereof positioned toward and spaced from the internal surface of said helmet whereby said surface reflects sound waves 115 against such movable parts.
3. In a telephone equipment, a helmet, a transmitter unit having movable parts arranged at one side thereof, and means engaging 120 said helmet to support said unit adjacent the mouth of a wearer of the helmet and with the movable parts of said unit on the opposite side thereof from the mouth of the wearer; said supporting means and unit co-operating to prevent sound waves due to 125 the respiration of the wearer affecting the movable parts of said unit.
4. In a helmet, a telephone transmitter unit having movable parts arranged at one side thereof, and means engaging said hel- 130

met to support said unit with said movable parts located between the inner wall of the helmet and said supporting means to co-operate with said unit to prevent moisture 5 due to respiration of a wearer of the helmet condensing on the movable parts of the transmitter unit.

5. In a helmet, a vent chamber therefor, a support of resilient material adapted to 10 be sprung into said vent chamber to engage the walls thereof, and a transmitter unit removably secured to said helmet by said supporting means.

6. In a helmet having a recess therein, a 15 transmitter unit having movable parts arranged at one side thereof, and supporting means having feet directed toward said recess and supporting the movable parts of said unit toward said recess whereby space 20 is provided between the legs of said supporting means to admit sound waves to said recess, said recess serving to reflect such waves against the movable parts of said unit to actuate the latter.

25 7. In a helmet, a vent chamber therefor, a telephone transmitter unit having movable parts arranged at one side thereof, and supporting means in said helmet to position the

movable parts of said unit toward said vent chamber said supporting means coöperating 30 with said vent chamber to decrease the volume of sound waves with respect to the movable parts of said unit.

8. In a helmet, a vent chamber therefor, a telephone transmitter unit having movable 35 parts arranged at one side thereof, and supporting means to engage said vent chamber to position the movable parts of said unit toward said chamber; said supporting means coöperating with said vent chamber to decrease the volume of sound waves with respect to the movable parts of said unit.

9. In a helmet, a vent chamber therefor, a telephone transmitter unit having movable 40 parts arranged at one side thereof, and supporting means in said helmet to position said unit between the mouth of the user and said vent chamber with the movable parts of said unit toward said vent chamber; said supporting means coöperating with said 45 unit and vent chamber to decrease the volume of sound waves with respect to the movable parts of said unit.

In witness whereof, I hereunto subscribe my name this 18th day of May, A. D. 1916. 55
CHARLES A. FINLEY.
